(57) **CLAIM**

The ornamental design for a fractal vise as shown and described.

DESCRIPTION

FIG. 1 is an isometric view of a fractal vise.

FIG. 2 is a top plan view of the fractal vise of FIG. 1.

FIG. 3 is a bottom view of the fractal vise of FIG. 1.

FIG. 4 is front view of the fractal vise of FIG. 1.

FIG. 5 a rear view of the fractal vise of FIG. 1.

FIG. 6 is a left side view of the fractal vise of FIG. 1; and, FIG. 7 is a right side view of the fractal vise of FIG. 1.

Portions of FIGS. 1 through 7 are shown in broken lines and dash-dot-dash boundary lines illustrating portions of the article that form no part of the claimed design.

1 Claim, 7 Drawing Sheets

FIG. 2

FIG. 3

FIG. 4

FIG. 5

FIG. 6

FIG. 7
